UNITED STATES PATENT OFFICE

EDWARD LEONARD REYNOLDS, OF TULSA, OKLAHOMA

AIRCRAFT EMPENNAGE

Application filed February 8, 1929. Serial No. 338,505.

This invention relates to an improved empennage for aeroplanes.

The primary object of the invention is to provide an empennage including foldable elements combined with novel means to permit the same to be stored within the tail of the fuselage, when the latter alights on the water, for example.

A further object is to furnish a sectional rudder, the sections of which, when assembled, are used for air navigation; one of the sections being used for water navigation, when the other section is stored within the hull or fuselage.

15 A further object is to provide an empennage having combined horizontal stabilizers and elevators which may also be drawn within and housed by the hull when the craft is used for water navigation.

20 Another object is to furnish an empennage of the above character with an adjustable vertical stabilizer or fin which co-operates with the rudder and may be stored within the hull when the craft alights on water.

25 A further object is to provide an empennage, all parts of which, with the exception of the lower part of the rudder may be stored within the hull in case the craft is forced to alight on the water. This will not alone 30 prevent breakage of such elements, but will keep the same from interfering with the stability of the craft in water navigation.

With the foregoing objects outlined and with other objects in view which will appear 35 as the description proceeds, my invention consists in the novel features hereinafter described in detail illustrated in the accompanying drawings, and more particularly pointed out in the appended claims.

40 Referring to the drawings,

Fig. 1 is a top plan view of my improved empennage.

Fig. 2 is a side elevation of the same, partly broken away, and with the various parts in 45 their normal positions.

Fig. 3 is a similar view with certain parts stored.

Fig. 4 is a rear elevation of the parts in 50 normal position, and shown cooperating with an aircraft that is in dot and dash lines.

Fig. 5 is an enlarged sectional view of certain details.

Fig. 6 is a horizontal sectional view of a detail, taken on line 6—6 of Fig. 2.

Fig. 7 is a vertical sectional view of a detail on the line 7—7 of Fig. 5. 55

Fig. 8 is a top plan view of the tiller bar.

Fig. 9 is an enlarged top plan view of a detail and showing the manner of connecting a part of the rudder support to the vertical stabilizer, or fin. 60

In the drawings, 1 designates the rear end of an aeroplane fuselage or hull, which is provided externally with a horizontal hinged platform or equalizer 2, having a longitudinally extending slot 3. A lower rudder section 4 (Fig. 2) is hinged at 5 to the stern post of the hull, and just below this post the tail skid or guard 6 is located. As shown in Fig. 5, the rudder section 4 is fast on a vertical shaft 7, which projects at its upper end into a tiller bar 8, that is fixed to the shaft. As is usual, this bar has oppositely extending arms 9 to which control mechanism (not shown) is attached to allow the rudder shaft to be turned from the pilot's station. When the aircraft is navigated on water, the rudder section 4 will function as an ordinary rudder for navigation purposes. 75

For the purpose of converting the section 4 into part of an aerial rudder, its opposite side surfaces converge toward its upper edge, as best shown in Fig. 7, and enters a recess 10 formed in the lower edge portion of an upper shiftable rudder section 11. This section is fixed to an upper rock shaft 12, which, as shown in Fig. 5, has a square lower end that is slidably mounted in a square socket 13, provided in the tiller bar. 80

A yoke 14 has upper and lower arms 15 and 16 in which the rock shaft 12 is journaled, and the rock shaft bears at its lower end upon an anti-friction thrust bearing 17, carried by the arm 16. It will be noted at this point, that the rock shaft extends 85 through a sleeve 18 which forms part of the upper rudder section 11, and is located between its front and rear end portions 19 and 20. As the upper and lower shafts 12 and 7 are clutched together by the tiller bar 90

8, obviously, when the bar 8 is moved, both rudder sections 4 and 11 will be simultaneously moved, and the front portion 19 of the upper section will rock within the yoke 14.

To permit the upper rudder section 11 to be shipped or stored within the hull, the lower corner of the yoke is fast on a shaft 21 which is provided with a fixed gear 22 that meshes with an operating gear on a shaft 24. I propose to turn the shaft 24 by a servo-motor (not shown), and from Figs. 2 and 3, it may be seen that when the servo-motor is operated to turn the wheel 23 in a counter-clock-wise direction, the upper section 11 of the rudder will be swung forwardly about the axis of the shaft 21, and the rudder will move through the slot 3 into the hull, where it may be stored, as shown in Fig. 3. Of course, when the rudder section 20 is in either its outboard or shipped position, it may be secured in such position by a suitable lock or brake.

It will also be noted that when the section 11 is swung forwardly with the yoke 14, the lower end of the shaft 12 will automatically disconnect itself from the tiller bar 8.

A vertical stabilizer or upwardly extending fin 25 cooperates with the yoke 14, and has its front end mounted on a horizontal shaft 26. This fin is of bifurcated construction, and is made up of spaced side plates 27

which are joined together at their front ends 28. This bifurcated construction allows the shiftable rudder section 11 to be swung forwardly and downwardly between the plates 27, when the section 11 is to be stored, and at this point it may be observed that the vertical stabilizer 25 normally projects upwardly through the slot 3 of the hinged equalizer.

When the parts are in normal position, a T-shaped head 29 on the yoke 14 interlocks with spaced lugs 30 on the rear ends of the stabilizer plates 27, and spring pressed latches 31 may be employed to hold the head in rigid engagement with the lugs. Of course, the latches may be actuated by any suitable means to permit them to be released from the pilot's station.

Any suitable form of latch 32, such as diagrammatically shown in Fig. 2, may be projected beneath the stabilizer 25 near its rear end, for the purpose of normally holding the stabilizer and yoke 14 rigidly in position, and like the latches 31, the latch 32 may be connected to suitable means to allow the same to be operated from the pilot's station.

As best shown in Fig. 1, the elevators 33 of the empennage are hinged by shafts 34 to horizontal stabilizers 35. The elevators may be rocked or folded over onto the stabilizers 35 by cable operated spools 37 fixed on the shafts, and for the purposes of the present invention, the elevators and stabilizers are adapted to be stored within the hull. To this end, each of the shafts 34 is mounted in a

bearing carried by a vertical shaft 36 which may be rocked by any suitable means, such as a servo-motor, and as these shafts are rocked for the purpose of storing the elevators and horizontal stabilizers, the inner ends of the shafts 34 automatically disconnect themselves from bearings 34^a carried by the deck. Before storing the elevators and horizontal stabilizers, the elevators 33 are folded over along their hinged joints on to the stabilizers 35, and then these parts are swung forwardly and inwardly through slots 38 which are located in the side of the hull, immediately above or below the deck (see Fig. 3).

Of course, the elevators and horizontal stabilizers cannot be stored until after the rudder section 11 and vertical stabilizer 25 have been stored, and when the latter is in stored position, its rear upper end will rest against a protruding end of the shaft 21. Obviously, the shaft 24 does not project entirely across the hull, for if it did, it would interfere with the storing of the parts.

To allow the stabilizers 35 and the elevators 33 which they carry, to be stored without interference by each other, one of the shafts 36 may be raised by a cam, as the shaft turns, so that one stabilizer and the elevator carried thereby will be elevated to a higher plane than the other, whereby these parts may be superposed while storing the same.

In actual practice, I prefer to make the shaft 26 fast to the front end of the vertical stabilizer 25, and to operate such shaft by a servo-motor or the like, so that this stabilizer may be raised or lowered by controls positioned at the pilot's station.

Those skilled in the art will appreciate that when an aeroplane having an empennage made in accordance with my invention, is forced to alight upon the water, the parts 11, 14, 25, 33 and 35 may be readily shipped to prevent the same from being damaged, and to also prevent the same from interfering with the stability and guiding of the hull on the water. This is particularly advantageous in rough water, for it will tend to prevent wind or waves from exerting capsizing forces on the empennage.

From the foregoing it is believed that the construction, operation and advantages of the invention may be readily understood by those conversant with aircraft, and I am aware that changes may be made in the details disclosed, without departing from the spirit of the invention, as expressed in the claims.

What I claim and desire to secure by Letters Patent is:

1. An empennage including a rudder consisting of upper and lower sections detachably connected together, a hull to which the rudder is connected, and means for detaching the upper section from the lower section, and for moving the upper section into the hull. 125

2. An aircraft empennage, including a hull, a rudder pivotally connected to the hull and consisting of upper and lower sections, and means for detaching the upper section from the lower section, and for moving the upper section into the hull. 50
3. An aircraft empennage, including a hull, a rudder pivotally connected to said hull and consisting of upper and lower sections, and 10 means for detaching the upper section from the lower section, and for swinging the upper section into the hull.
4. In an aircraft empennage, a pivoted rudder and a movable up-standing vertical stabilizer, and means pivotally mounting the stabilizer to permit the same to be stored in the hull. 15
5. In an aircraft empennage, a hull, a rudder pivotally connected to the hull and including upper and lower sections detachably connected together, a yoke carrying the upper section, and means for moving the yoke and upper section into the hull. 20
6. An aircraft empennage, including a hull, 25 a rudder pivotally mounted on the hull and including upper and lower sections detachably connected together, a shaft for each section, and clutching means connecting said shafts together.
7. An aircraft empennage, including a hull, 30 a rudder pivotally mounted on the hull and including upper and lower sections detachably connected together, a shaft for each section, and a tiller bar detachably connecting the shafts together.
8. An aircraft empennage, including a hull, 35 a rudder pivotally mounted on the hull and consisting of upper and lower sections detachably connected together, means for moving said sections in unison, and a carrying member for the upper section, pivotally mounted on the hull for movement about a horizontal axis.
9. An aircraft empennage, including a hull, 45 a rudder pivotally mounted on the hull and consisting of upper and lower sections detachably connected together, a yoke carrying the upper section, a shaft on which the yoke is mounted, and means for rotating said shaft for moving the upper section and yoke into the hull. 50
10. In an aircraft empennage, a rudder member and a stabilizer member, each of said members being mounted for movement about parallel axes, one of said members including spaced side plates and the other member being adapted to move into the space between said side plates. 55
11. In an aircraft empennage, a hull, a rudder member and a stabilizer member, means for detachably connecting said members together, mounting means for the members including horizontal shafts, one of said members having spaced side plates, and the other 60
- member being adapted to be moved into the hull and stored between said side plates. 70
12. An aircraft empennage, including a hull, a rudder support pivotally mounted on the hull for movement about a horizontal axis for the purpose of storing the rudder within the hull, a stabilizer pivotally mounted on the hull and adapted to support the yoke in one position, said stabilizer including spaced side plates between which the yoke and rudder 75 may be moved into the hull. 75
13. An aircraft empennage, including pivotally connected elevators and horizontal stabilizers, a hull, means connecting said elevators and stabilizers to the hull, and means to permit said elevators and stabilizers to be moved to a stored position within the hull without separating the last mentioned connecting means. 80
14. An aircraft empennage, including a hull, horizontal stabilizers mounted on the hull and adapted to be moved from a position exteriorly of the hull to a position within the hull, horizontal shafts connected to the stabilizers, elevators mounted on said shafts, and means supporting said shafts for movement about vertical axes. 85
15. An aircraft empennage including a hull, horizontal stabilizers mounted on the hull and adapted to be moved from a position exteriorly of the hull to a position within the hull, horizontal shafts connected to the stabilizers, elevators mounted on said shafts, means to permit the inner ends of said shafts to be rotated, and means for supporting said shafts for movement about vertical axes arranged within the hull. 90
- In testimony whereof I affix my signature.
